UNITED STATES PATENT OFFICE.

THADIOUS VENSON ELLIOTT, OF COLUMBIA, PENNSYLVANIA, ASSIGNOR OF ONE-HALF TO JOHN B. HUTCHINSON, OF COLUMBIA, PENNSYLVANIA.

FEED-WATER HEATER AND PURIFIER.

SPECIFICATION forming part of Letters Patent No. 746,479, dated December 8, 1903.

Application filed July 3, 1902. Serial No. 114,223. (No model.)

To all whom it may concern:

Be it known that I, THADIOUS VENSON ELLIOTT, a citizen of the United States, and a resident of Columbia, in the county of Lancaster and State of Pennsylvania, have made certain new and useful Improvements in Feed-Water Heaters, of which the following is a specification.

My invention is an improvement in feed-water heaters for use in connection with steam-boiler furnaces; and the invention consists in certain novel constructions and combinations of parts, as will be hereinafter described and claimed.

15 In the drawings, Figure 1 is a perspective view, partly in section and parts being removed, of an apparatus embodying my invention. Fig. 2 is a front elevation of the steam-boiler and furnace, parts being removed and others shown in section, provided with my invention. Fig. 3 is a detail cross-section on about line 3-3 of Fig. 2, and Fig. 4 is a detail section showing the lower connection of the water-pipes with the boiler.

20 The boiler A and the furnace B may in general respects be of ordinary construction, the boiler A having the flues a and the furnace B the grate-bars b and means being provided for firing the furnace.

25 By my invention I provide two manifolds C C, supported one at each side of the furnace B, with their lower ends or horizontal tubes D below the grate-bars b and their upper ends or tubes E above the said grate-bars and the upright connecting-tubes F, which extend in series between the tubes D and E, extending within the side walls G of the furnace and exposed at their inner sides to the action of the heat of the furnace, the said upper tubes F opening into the furnace at their inner sides, as best shown in Fig. 3. It will be understood that the tubes D and E also are exposed at their inner sides within the furnace and by arranging the tubes D below the grate-bars and the tubes E above said grate-bars an upward circulation of the water is secured within the manifolds by reason of the greater degree of heat at the upper ends thereof. At their rear ends the lower tubes D of the opposite manifolds are

connected by a cross-tube d, which increases the water capacity of the heater and forms a direct connection between the water-tubes at the lower sides of the furnace. Water is supplied to the feed-water heater from a pump 55 or other source of supply through a pipe H, having branches I connecting with the outer ends of the lower tubes D of the manifolds, such ends of the tubes D being inclosed by the plugs J, which may be removed for the 60 purpose of cleaning out the manifolds whenever desired. Water is supplied from the heater to the boiler by means of the tubes K, leading from the upper rear ends of the manifolds to the under side of the boiler and discharging thereto at K', as shown, a suitably-valved discharge being provided at K² for blow-off purposes. The upper front ends of the manifolds are connected by pipes L with the front end of the boiler above the water-line opening into the steam-space of the boiler and co-operating with the pipes K in securing a circulation within the feed-water heater to prevent any burning out of the latter.

65 In operation the water supplied to the feed-water heater will be raised to a comparatively high temperature before being discharged into the boiler, and by reason of the upward circulation of the water in the manifolds the water will be purified within the 70 feed-water heater before being delivered into the boiler as is desired.

Having thus described my invention, what I claim as new, and desire to secure by Letters Patent, is—

85 1. An apparatus substantially as described comprising in combination with the boiler a furnace, and the side walls of the furnace, the opposite manifolds partly seated in the walls of the furnace and composed each of 90 the lower tube arranged below the grate of the furnace, the upper tube above the grate of the furnace, the upright connecting-tubes between the upper and lower tubes and exposed at their inner sides within the furnace, 95 the cross-tube connecting the rear ends of the lower tubes and extending beneath the grate of the furnace, the feed-pipe having branches leading to the front ends of the lower tubes, water-pipes leading from the 100

upper rear ends of the manifolds to the boiler below the water-line of the boiler, and the connecting-pipes between the upper front ends of the manifolds and the boiler above the 5 water-line of the latter substantially as and for the purpose set forth.

2. The combination of the boiler, the furnace, the manifolds arranged at the opposite sides of the furnace and comprising the lower 10 tubes below the furnace-grate and the upper tubes above said grate, the cross-tube connecting the rear ends of the lower tubes of the manifolds, the plugs at the front ends of said tubes, the water-supply pipes connected 15 with the front ends of the lower tubes and connections between the upper tubes of the

manifolds and the boiler substantially as and for the purposes set forth.

3. The combination of the furnace and boiler, the manifolds arranged at the opposite 20 sides of the furnace and having lower longitudinal tubes, upper longitudinal tubes and connecting-tubes extending between said upper and lower tubes, connections between the manifolds and the boiler and the feed-pipe having portions connecting with the front ends of the lower longitudinal tubes, substantially as set forth.

THADIOUS VENSON ELLIOTT.
